UNITED STATES PATENT OFFICE.

ARTHUR L. DEDI, OF OAK PARK, ILLINOIS.

DESIGN FOR A LAMP-ARM MOUNTING.

Application filed March 24, 1923. Serial No. 5,579. Term of patent 3½ years.

To all whom it may concern:

Be it known that I, ARTHUR L. DEDI, a citizen of the United States, residing in the village of Oak Park, in the county of Cook and State of Illinois, have invented a new, original, and ornamental Design for a Lamp-Arm Mounting, of which the following is a specification, reference being had to the accompanying drawing, forming part thereof, and in which the mounting is illustrated in side view as applied to a conventional form of lamp arm indicated by dotted lines.

I claim:

The ornamental design for a lamp arm mounting substantially as shown.

ARTHUR L. DEDI.
